ATTORNEY.

UNITED STATES PATENT OFFICE

CHARLES H. REEDER, OF ST. LOUIS, MISSOURI, ASSIGNOR TO REEDER MANUFACTURING CO., OF ST. LOUIS, MISSOURI, A CORPORATION OF MISSOURI

CHAPLET

Application filed June 3, 1929. Serial No. 367,865.

This invention relates to chaplets for use in foundry work to support cores in molds which are prepared to receive molten metal.

Chaplets should have sufficient strength to support heavy cores without deflection which would vary the thickness of the casting. It is also desirable to make the chaplets of thin metal which will be fused by and integrally united with the molten metal, so as to prevent the formation of weak portions in the casting.

Prior to the present invention some of these results have been more or less effectively obtained by chaplets made of thin sheet metal. However, to provide the desired strength, wide sheet metal walls have been located in the course of the molten metal, which tends to displace the chaplets, and such walls also tend to trap gas and steam in the chaplets, thereby resulting in "blow holes" and porous conditions which weaken the casting at the chaplets. Moreover, wide solid walls in a chaplet tend to quickly chill the molten metal and they do not become fused or integrally united with the casting to the same degree that thin narrow strips would be united therewith.

One of my objects is to produce a chaplet of thin metal having the desired strength, and which is in the form of an open skeleton through which the gases, steam and molten metal will pass freely, without being obstructed by wide baffles, or the like.

More specifically stated, my object is to most effectively accomplish all of these results, by means of a simple and inexpensive chaplet consisting of open top and bottom members and a strong group of thin, narrow members separating the top and bottom members. The molten metal will quickly flow between and around the thin narrow members, uniting the whole mass by fusion in the hot metal. However, the continuity of the cast metal is not materially interrupted by the thin, narrow skeleton members in the chaplet, so the resultant casting is free from defects at the chaplets, and this casting may be used as a container for liquid or gaseous fluids without danger of leakage at the chaplets.

Another object is to produce a chaplet hav-

ing a simple and inexpensive anchoring means whereby it can easily and quickly be anchored in the mold.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is a perspective view of a chaplet embodying the features of this invention.

Fig. 2 is a side elevation.

Fig. 3 is a section through the middle portion of the chaplet.

Fig. 4 is a top view.

Fig. 5 is a front view.

Fig. 6 is a section showing the chaplet in a casting, the plane of the section being at one side of the separating tongues.

Fig. 7 is a plan view of the strip of metal which is bent to form the chaplet.

The chaplet shown to illustrate one form of the invention comprises top and bottom members 1, an intermediate member 2 connecting said top and bottom members, and separating members 3 cooperating with said intermediate member to prevent downward displacement of the top member relative to the bottom member. All of these parts may be made of a single sheet of metal (Fig. 7) bent to the desired shape and punched to form the separating members 3 which preferably lie at an angle to the top and bottom members 1, and also at an angle to the connecting member 2.

The top and bottom faces of the chaplet are preferably flat and parallel with each other.

The connecting member 2 extends downwardly from one side of the top member to the opposite side of the bottom member, and this connecting member may be inclined as shown to cooperate with the top and bottom members in forming a Z-shaped article. The separating members 3 are in the form of

tongues punched from the top and bottom members. The upper separating tongue 3 lies between the top member and the connecting member 2 so as to prevent downward displacement of said top member relative to said connecting member. The lower separating tongue 3 lies between the connecting member 2 and the bottom member 1 to prevent downward displacement of the connecting member relative to the bottom member.

15 Attention is now directed to open construction of the chaplet consisting of thin and narrow members producing an open skeleton frame which does not obstruct the flow of the molten metal, and does not trap 20 the air ahead of the molten metal nor the steam and gases which are often generated when the molten metal contacts with the chaplets. Moreover, the narrow skeleton members do not materially chill the molten 25 metal and they are readily fused by this hot metal to become an integral part of the casting.

30 Either of the members 1 may be located at the top of the chaplet, and each of said members is in the form of a web having a large opening 4 to receive the molten metal and to permit the escape of steam and gases from the chaplet.

35 The connecting member 2 is in the form of an approximately H-shaped web comprising side members separated from each other to permit free flow of gases and molten metal between them, and an intermediate member 5 uniting said side members. The large openings in this H-shaped connecting web 2 extend into edges of the top and bottom members 1, as shown at 6 in Figs. 1 and 3. Consequently, the top and bottom members are open at connecting web 2 to permit free flow 45 of gases and molten metal. The gases escape at the top member, instead of being trapped at the upper edge of the inclined connecting member, and the molten metal flows along the inner faces of the top and bottom member and freely passes through the large openings at the upper and lower portions of the connecting member 2.

50 The separating tongues 3 are provided with openings at 7 which extend to the respective top and bottom members. These openings aid in venting the chaplet while permitting free flow of the molten metal, and they leave narrow metal members which fuse into without unduly chilling the molten 60 metal.

65 The chaplet herein described is a strong and simple device made of inexpensive sheet metal which can be easily punched as shown in Fig. 7, and then bent in a forming die to produce an article having absolutely parallel

70 top and bottom faces accurately separated to lie at a predetermined distance from each other. The simple skeleton structure is so braced that it will withstand severe crushing stresses without material deflection, and although the narrow sheet metal members may be relatively thin, they have no weak overhanging portions likely to be bent by the weight of a heavy core. The device shown is also open at all sides to freely receive the 75 molten metal without liability of trapping gas, or the like, in the chaplet. The thin, narrow members are readily fused by, or welded to, the casting, and owing to the peculiar shape of the chaplet structure, it will not 80 materially weaken the casting, even in cases where the molten metal is not hot enough to cause the desired degree of fusion. This is suggested in Fig. 6 which shows how the casting 8 surrounds and interlocks with the skeleton chaplet to avoid the production of 85 weak lines of fracture.

90 Chaplets are made in numerous sizes for use in making castings differing in thickness, and another advantage of the structure shown lies in the fact that in an emergency it can be forcibly compressed in a vise, or the like, to meet the requirements of several other sizes and still retain its strength and its parallel 95 top and bottom faces. The separating tongues 3 are offset from each other at the narrow intermediate member 5, as shown in Fig. 3, and this narrow member will yield in response to pressure transmitted through the tongues 3, so as to provide for the above 100 mentioned forcible compression which reduces the distance between the top and bottom members.

105 Prior to this invention, nails have been used to secure chaplets in molds, the nails being passed through the chaplets and driven into the sand. To reduce the time and labor involved in securing the chaplet, I have shown 110 anchoring means integral with the chaplet structure adapted for use whenever it is desired to fasten the chaplet in a mold.

115 To illustrate this feature, anchoring prongs 9 and 10 are shown on one of the members 1. The prong 10 is punched from the opening in one of the separating tongues 3, and this prong 10 may extend into the opening 4 in the top member 1 where it lies parallel with 120 said top member, or the said prong 10 may be bent to the anchoring position shown by dotted lines in Fig. 3.

125 The integral prongs 9 extend from the side margins of one end of the strip of metal forming the chaplet, as shown in Fig. 7, and the other end of the strip is cut away at its side margins to provide corresponding prongs for another chaplet which is punched from the stock adjoining this strip. The prongs 9 may lie parallel with the flat member 1 from which they extend, and when they are required to secure the chaplet, said prongs 130

9 are bent as indicated by dotted lines in Fig. 3, to extend from the flat face. The chaplet can be secured by merely forcing it onto the sand with pressure sufficient to force the extended prongs into the sand.

I claim:

1. A chaplet comprising a top member, a bottom member, and a connecting member extending from said bottom member to one edge 10 of said top member, said edge being provided with a vent opening for the discharge of gases from the chaplet.

2. A chaplet comprising a top web, a bottom web, a web connecting said top and bottom web, said connecting web comprising side members separated from each other to permit free flow of gases and molten metal between them and an intermediate member uniting said side members, and separating 20 tongues extending from said intermediate member to the top and bottom webs, said separating tongues being offset from each other at the intermediate member, and the latter being yieldable in response to pressure transmitted through said tongues to provide for 25 a variation in the distance between said top and bottom webs.

3. A chaplet having an opening for the discharge of gases therefrom and an anchoring 30 prong in said opening, said prong being flexible and adapted to be bent to an anchoring position outside of said opening.

4. A chaplet comprising a continuous strip 35 of metal having one of its ends at the top of the chaplet and its opposite end at the bottom of the chaplet, one of said ends being provided with an extended anchoring prong and the other end being cut away to provide a corresponding prong on another chaplet.

40 5. A chaplet comprising a continuous strip of metal having one of its ends at the top of the chaplet and its opposite end at the bottom of the chaplet, one of said ends being provided with anchoring prongs at the side margins of the chaplet, and the other end being cut away at its side margins to provide corresponding prongs for another chaplet.

6. A chaplet comprising a top member, a bottom member, and a connecting member extending from said bottom member to one edge 50 of said top member, said connecting member having an opening extending into said top member.

7. A chaplet comprising a top member, a bottom member, and a connecting member extending from one edge of said top member to the opposite edge of said bottom member, said connecting member having openings extending 55 into said top and bottom members.

8. A chaplet comprising a top member, a bottom member and a connecting member extending from one edge of said top member to the opposite edge of said bottom member, said connecting member comprising relatively 60 thin and narrow web members separated from

each other to permit free flow of fluid and gases between them.

9. A chaplet comprising a top web member having a relatively large opening, a bottom web member having a relatively large opening, a connecting member extending from one edge of said top member to the opposite edge of said bottom member, said connecting member comprising relatively thin and narrow web members separated from each other to permit free flow of gases and molten metal between them and a relatively narrow and thin intermediate member uniting the last mentioned web members, and separating 70 tongues extending from said intermediate member to said top and bottom members, said separating tongues comprising relatively thin and narrow web members.

In testimony that I claim the foregoing I hereunto affix my signature.
